US0D1026613S

(12) **United States Design Patent** (10) **Patent No.:** **US D1,026,613 S**
(45) **Date of Patent:** **** May 14, 2024**

(54) **LOCKING DEVICE**

- (71) Applicant: **Endura Products, LLC**, Colfax, NC (US)
(72) Inventor: **George E. Heid**, Charlotte, NC (US)
(73) Assignee: **ENDURA PRODUCTS, LLC**, Colfax, NC (US)

(**) Term: **15 Years**

(21) Appl. No.: **29/833,019**

(22) Filed: **Mar. 31, 2022**

Related U.S. Application Data

- (63) Continuation of application No. 17/125,173, filed on Dec. 17, 2020, which is a continuation of application No. 17/125,067, filed on Dec. 17, 2020, which is a continuation of application No. 15/828,640, filed on Dec. 1, 2017, now Pat. No. 10,876,324.
